Design No. 12,321, dated June 21, 1881.

UNITED STATES PATENT OFFICE.

SAMUEL N. GOODMAN, OF PHILADELPHIA, PA., ASSIGNOR TO CONYERS
BUTTON AND THEODORE A. FLEU, OF SAME PLACE.

DESIGN FOR A KNITTED FABRIC.

SPECIFICATION forming part of Design No. 12,321, dated June 21, 1881.

Application filed May 11, 1881. Term of patent 7 years.

To all whom it may concern:

Be it known that I, SAMUEL N. GOODMAN, a citizen of the United States, residing in Philadelphia, Pennsylvania, have invented a new and original Design for a Knitted Fabric, of which the following is a specification.

My design for a knitted fabric is fully shown in the accompanying drawings, in which—

Figure 1 is a photographic illustration of a piece of the fabric, and Fig. 2 a sectional view of part of the same.

The main features of the design are the parallel rows of tufts *a* and *b*, the tufts *a* being on one side of the fabric and the tufts *b* on the opposite side. These tufts are carried by a groundwork consisting, in the present instance, of vertical looped cords and lateral connecting threads; but the character of the groundwork may be varied to some extent without detracting from the essential characteristic of the design.

In the fabric shown in the drawings, single rows of tufts *a* on one side of the fabric alter-

nate regularly with rows of tufts *b* on the opposite side; but this exact arrangement may be modified in practice—for instance, double rows of tufts may be employed instead of single rows, or two or more rows of tufts *a* may alternate with a single row of tufts *b*. A uniform alternation is preferred, however, in order that both sides of the fabric may present a similar appearance.

Irrespective of the colors employed, I claim—

The design for a knitted fabric, said design comprising a groundwork on which are arranged rows of tufts *a* and *b*, the tufts *a* being on one side of the fabric and the tufts *b* on the opposite side of the same, all substantially as shown and described.

In testimony whereof I have signed my name to this specification in the presence of two subscribing witnesses.

SAMUEL N. GOODMAN.

Witnesses:

W.M. P. LOGAN,
HARRY SMITH.
